Primary Examiner — Jennifer L Watkins(74) *Attorney, Agent, or Firm* — Clement Cheng**CLAIM**

The ornamental design for an animal backpack as shown and described.

DESCRIPTION

FIG. 1 is a perspective view of an animal backpack.

FIG. 2 is a front view of the animal backpack.

FIG. 3 is a rear view of the animal backpack.

FIG. 4 is a left side view of the animal backpack.

FIG. 5 is a right side view of the animal backpack.

FIG. 6 is a top view of the animal backpack.

FIG. 7 is a bottom view of the animal backpack; and, FIG. 8 is a front view of the animal backpack with the arms detached.

The heavy dashed broken lines depicting zipper track form no part of the claim. The stitching forms no part of the claim. All other broken lines depict portions of the backpack and form no part of the claim.

1 Claim, 8 Drawing Sheets(56)
